(57) **CLAIM**

We claim the ornamental design for a display screen with transitional graphical user interface for a gantt chart, as shown and described.

DESCRIPTION

This application is a continued prosecution application (CPA) of U.S. Design patent application Ser. No. 29/708020, filed Oct. 2, 2019, entitled “User Interface for Gantt Chart”, the entire disclosure of which are incorporated herein by reference.

FIG. 1 is a front view of a first image in a sequence for a display screen with transitional graphical user interface for a gantt chart;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof; and,

FIG. 9 is a front view of a ninth image thereof.

The broken lines showing the display screen form no part of the claimed design. The remaining broken lines showing portions of the graphical user interface form no part of the claimed design. The dotted broken lines showing text form no part of the claimed design.

The appearance of the image transitions sequentially between the images shown in FIGS. 1-9. The process or period in which an image transitions to another forms no part of the claimed design.
